CLAIM

The ornamental design for a tool for disengaging a terminal fitted in a connector housing, as shown.

DESCRIPTION

FIG. 1 is a perspective view of a tool for disengaging a terminal fitted in a connector housing, showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

FIG 1

FIG 2

FIG 3

FIG 4

FIG 5

FIG 6
